G. R. NETTLETON.
SEPARABLE FASTENER.
APPLICATION FILED OCT. 6, 1916.

1,214,945.

Patented Feb. 6, 1917.

THE NORRIS PETERS CO., PHOTO-LITHO., WASHINGTON, D. C.

UNITED STATES PATENT OFFICE.

GEORGE R. NETTLETON, OF NEW HAVEN, CONNECTICUT, ASSIGNOR TO THE W. & E. T. FITCH CO., OF NEW HAVEN, CONNECTICUT, A CORPORATION.

SEPARABLE FASTENER.

1,214,945.

Specification of Letters Patent.

Patented Feb. 6, 1917.

Application filed October 6, 1916. Serial No. 124,181.

To all whom it may concern:

Be it known that I, GEORGE R. NETTLETON, a citizen of the United States, residing at New Haven, in the county of New Haven and State of Connecticut, have invented a new and useful Improvement in Separable Fasteners; and I do hereby declare the following, when taken in connection with the accompanying drawings and the characters of reference marked thereon, to be a full, clear, and exact description of the same, and which said drawings constitute part of this application, and represent, in—

Figure 1 a top or plan view of a separable fastener constructed in accordance with my invention.

Fig. 2 a side view of the same.

Fig. 3 a sectional view on the line 3—3 of Fig. 1.

Fig. 4 a sectional view on the line 4—4 of Fig. 1.

Fig. 5 a similar view with the lever in its open position.

Fig. 6 an end view of the post, detached.

Fig. 7 a plan view of the casing with the lever removed.

Fig. 8 a side view of the same.

Fig. 9 a perspective view of the lever, detached.

Fig. 10 a plan view of the washer used in connection with a separable fastener.

This invention relates to an improvement in separable fasteners, and while the device is particularly adapted for use as a curtain fastener, it is obviously adapted for use for other purposes.

The object of this invention is to provide a fastener particularly adapted for fastening curtains and pockets of automobiles, which is comparatively flat and easily engaged and disengaged, and with the minimum number of parts; and the invention consists in the construction hereinafter described and particularly recited in the claims.

In carrying out my invention I employ a casing 11 preferably struck up from sheet metal with integral prongs 12 by which it may be secured in place. In the upper face 50 of the shell is a clearance opening 13 into one end of which projects a finger 14 formed integral with the casing, and at the side of the opening opposite the finger the metal is depressed to form a wide groove 15. The lever 16 is formed on opposite sides with

inwardly projecting arms 17 the edges 18 of which are turned inward, forming segmental flanges. Preferably and as shown in Fig. 3 of the drawings, the arms will be slightly bowed. This lever is formed with a slot 19 corresponding in width to the width of the finger 14 which finger is curved through the slot so as to hinge the lever in the casing. The lever is formed with a finger-piece 20 corresponding in width to the width of the groove 15 into which it is set, the depth of the groove corresponding to the thickness of the metal from which the lever is formed so that when the lever is in the closed position it will stand flush with the upper face of the casing, the said finger projecting slightly beyond the outer wall of the casing. By slightly bowing the sides of the arms of the lever the said arms form springs which will yield to permit the lever to be turned in its closed position through the opening 13 in the casing, and yet when turned into the closed position the bowed sides of the arms will tend to hold the lever in the closed position. The casing is applied to a curtain 21 or other device by forcing the prongs 12 through the curtain and upsetting them over a washer 22 corresponding in shape to the shape of the casing and formed with a clearance hole 26, the portion of the curtain inclosed by the casing being cut away in the usual manner. This fastener is used in connection with a post 23 formed on opposite sides near its upper ends with grooves 24 forming a head 25 the lower edges of the projecting portions of the head being curved as clearly shown in Figs. 4 and 5 of the drawings. The post may be driven, screwed or riveted in position so that it will project to proper extent to be engaged by the flanges 18 of the lever. To secure the fastener the lever is opened as shown in Fig. 5 of the drawings, and the device set over the post which extends through the hole 21 in the washer and into the casing 11. The lever is then turned down into its closed position as shown in Fig. 4 of the drawings, and as it is turned down the flanges 18 of the arms 17 enter the grooves 24 of the post and engage with the lower edges of the head thereof so as to draw the fastening device closely against the portion in which the post is mounted, and as before stated, the sides of the arms when extended being slightly greater than 110

the width of the opening 13. In the closed position the finger-piece 20 of the lever stands in the groove 15 and slightly projects beyond the end of the casing so as to be conveniently lifted when it is desired to disconnect the fastener.

It will be noted that the fastener complete, with the post and washer, comprises only four separate pieces, the casing, lever 10 and washer being readily struck from sheet metal, thus enabling the fastener to be produced at a very low cost.

Obviously one of the arms on the lever might be omitted, although preferably two 15 arms will be employed.

I claim:—

1. A separable fastener comprising a casing provided with means for securing it in position, said casing formed in its outer 20 face with an opening, a lever pivotally connected with the casing and formed on opposite sides with arms adapted to extend through the said opening into the casing, combined with a post independent of the 25 casing with which said arms are adapted to engage.

2. A separable fastener comprising a casing, means for securing it in position, said casing formed in its outer face with an 30 opening, a lever pivotally connected with the casing and formed on opposite sides with arms adapted to enter the casing through the opening in the top thereof, said arms each formed with inwardly projecting 35 curved flanges, and a post independent of the casing with which said lever is adapted to engage.

3. A separable fastener comprising a casing provided with means for securing it 40 in place, said casing formed in its outer face with an opening, a lever pivotally connected with the casing and formed on opposite sides with arms extending through said opening, the edges of said arms formed 45 with inwardly projecting curved flanges,

combined with a post independent of the casing having a head beneath which said flanges are adapted to pass.

4. A separable fastener comprising a casing provided with means for securing it 50 in place, said casing formed in its outer face with an opening, a lever pivotally connected with the casing and formed on opposite sides with side walls adapted to enter the casing through the opening in the face 55 thereof, said side walls slightly bowed in a vertical plane, combined with a post independent of the casing with which said lever is adapted to engage.

5. A separable fastener comprising a casing provided with means for securing it in place, said casing formed in its outer face with an opening, an integral finger projecting into the said opening from one end thereof, a lever corresponding in width to 60 the width of said opening, said lever formed with a slot through which said finger extends, and whereby said lever is pivotally connected with the casing, said lever formed on opposite sides with inwardly projecting 65 arms, and a post independent of the casing with which said arms are adapted to engage when the lever is in the closed position.

6. A separable fastener comprising a casing provided with means for securing it in 75 position, said casing formed in its outer face with an opening, a lever pivotally connected with the casing and formed with an arm adapted to extend through the said opening into the casing, combined with a 80 post independent of the casing with which said arm is adapted to engage.

In testimony whereof, I have signed this specification in the presence of two subscribing witnesses.

GEO. R. NETTLETON.
